UNITED STATES PATENT OFFICE.

DANIEL I. TOMPKINS, OF NEW YORK, N. Y.

DESIGN FOR A BED-SPRING.

No. 37,649.

Specification for Design.

Patented Nov. 7, 1905.

Application filed May 3, 1905. Serial No. 258,734. Term of patent 14 years.

To all whom it may concern:

Be it known that I, DANIEL I. TOMPKINS, a citizen of the United States, residing at New York, in the county of New York and State of New York, have invented a new, original, and ornamental Design for a Bed-Spring, as shown in the accompanying drawing, which represents a transverse section of my design for a bed-spring.

I claim—
The ornamental design for a bed-spring as shown.

DANIEL I. TOMPKINS.
